Application April 26, 1935, Serial No. 18,306

11 Claims. (Cl. 171—119)

Our invention relates to transformers, and particularly to reactive transformers having an adjustable equivalent reactance.

One object of our invention is the provision, in a transformer of the type described, of novel means for adjusting the equivalent reactance of the transformer, whereby the range of adjustment of the transformer is increased and a continuous adjustment is provided between the maximum and minimum reactance.

We will describe several forms of transformers embodying our invention, and will then point out the novel features thereof in claims.

In the accompanying drawings, Fig. 1 is a front elevational view showing one form of transformer embodying our invention. Fig. 2 is a left-hand end view of the transformer shown in Fig. 1. Fig. 3 is a top view of the transformer shown in Figs. 1 and 2. Fig. 4 is a detail view of the bracket 4 forming part of the transformer illustrated in the preceding views. Figs. 5 and 6 are front elevational and left-hand side views, respectively, showing another form of transformer embodying our invention. Figs. 7, 8 and 9 are detail views showing certain of the laminations which are employed in constructing the core of the transformer shown in Figs. 5 and 6. Figs. 10 and 11 are front elevational and left-hand end views, respectively, showing a third form of transformer embodying our invention. Figs. 12, 13 and 14 are front elevational, right-hand end, and top views, respectively, showing a fourth form of transformer embodying our invention.

Similar reference characters refer to similar parts in each of the several views.

Referring first to Figs. 1 to 4, inclusive, the transformer here illustrated, which transformer is designated as a whole by the reference character T¹, comprises a stationary core member 1 of magnetizable material and a movable core member 2 which is also of magnetizable material. The stationary core member 1 is preferably laminated for obvious reasons, and comprises three vertically disposed spaced parallel legs 1^a, 1^b and 1^c connected together at their lower ends by a backstrap 1^d. The middle leg 1^b of the stationary core member 1 is surrounded by a primary winding P, while one of the outer legs, here shown as the leg 1^a, is surrounded by a secondary winding S.

The movable core member 2 is also preferably laminated, and in the form here shown is substantially rectangular in shape. It is mounted for longitudinal sliding movement between two guide plates 3 and 4 which are secured to the op-

posite sides of the stationary core member 1, at the upper ends of the legs of this core member, by means of certain ones of the bolts 5 which fasten the laminations of the stationary core member together. Provided adjacent the opposite ends of the movable core member 2 are through bolts 6 and 7, which bolts secure the laminations of the movable core member together, and also cooperate with the inner ends of two pairs of aligned slots 3^a, 4^a and 3^b, 4^b, provided in the guide plates 3 and 4, to limit the extreme positions to which the core member 2 may be moved. To facilitate moving the core member 2, a screw-threaded rod 8 is provided. This rod is fastened at one end to the movable core member 15 by means of the bolt 8, and is provided at the other end with a thumb nut 9 which is rotatably mounted in a lateral extension 3^c formed on the guide plate 3. The portion of the thumb nut which rotates in the extension 3^c has a smaller exterior diameter than the remainder of the thumb nut, whereby longitudinal movement of the thumb nut relative to the extension is prevented. It will be apparent that by turning the thumb nut in opposite directions the movable core member may be moved to any desired position 20 between its two extreme positions. A bolt 10 passes through the plates 3 and 4 above the core member in such manner that by tightening this bolt the movable core member may be clamped 25 in any desired position to which it is moved by the thumb nut.

With the transformer constructed in the manner just described, it will be apparent that two parallel flux paths are provided for the flux which is set up by the primary winding P when this winding is energized, one of which paths passes through the secondary winding S and includes the left-hand half of the backstrap 1^d, as viewed in Fig. 1, the leg 1^a, and the left-hand end of the movable core member 2, and the other of which paths is a leakage path and includes the right-hand half of the backstrap 1^d, as viewed in Fig. 1, the leg 1^c, and the right-hand end of the movable core member 2. It will also be 40 apparent that the flux which is set up in the core by the energization of the primary winding P will divide between the two paths just traced in proportion to the relative reluctances of these paths. The parts are so proportioned that when 45 the movable core member occupies its extreme position in which it is shown in the drawings, the leakage path will have a relatively low reluctance and the path through the secondary winding will have a relatively high reluctance, whereas, 50 55

when the movable core member occupies its other extreme position, the leakage path will then have a relatively high reluctance and the path through the secondary winding will have a relatively low reluctance. It follows, therefore, that when the movable core member occupies the extreme position in which it is shown in the drawings, substantially all of the magnetic flux from the primary winding will traverse the leakage path, and under these conditions, the secondary winding will have its maximum reactance, and the voltage regulation of the transformer will be substantially the same as that of a constant potential transformer with maximum reactance in series with the secondary winding. When, however, the movable core member occupies its other extreme position, substantially all of the magnetic flux from the primary winding will then traverse the path through the secondary winding, and under these conditions, the secondary winding will have its minimum reactance, and the voltage regulation of the transformer will approach that of a constant potential transformer. It will readily be understood that by moving the movable core member between its two extreme positions, the reluctance of the two flux paths may be gradually varied between their maximum and minimum values, and that as the reluctance of one path increases, the reluctance of the other path will simultaneously decrease, and it is evident, therefore, that by changing the position of the movable core member 2, the equivalent reactance of the secondary winding S may be varied by infinitely small amounts to give any desired value between its maximum and minimum equivalent reactance, which value may be maintained by clamping the movable core member 2 in its adjusted position by means of the bolt 10.

As shown in Fig. 1, a portion of the movable core member 2 adjacent each end is cut away to provide an inclined surface 2^c. The function of these inclined surfaces is to cause the reluctances of the two magnetic paths to vary uniformly as the movable member is moved from either extreme position to the other extreme position.

Referring now to Figs. 5 and 6, we have shown a slightly different form of transformer which will produce the same results as the transformer T¹ shown in Fig. 1. This transformer, which is designated as a whole by the reference character T², comprises a magnetizable stationary core member 11 and a magnetizable movable core member 12. The stationary core member 11 consists of a plurality of E-shaped laminations, each similar to the lamination 13 shown in Fig. 7, stacked on each side of, and secured to, a plurality of E-shaped laminations, each similar to the lamination 14 shown in Fig. 8. The laminations 13 are all stacked with their open ends extending downwardly, and are provided at their upper ends with slots 13^a and 13^b which reduce the magnetic section between the middle and two outer legs. The laminations 14 are shorter than the laminations 13, and are each disposed with their open ends extending upwardly. With the stationary core member constructed in this manner, it will be apparent that it is provided with three vertically extending legs 11^a, 11^b and 11^c, the lower ends of which are connected together by a relatively low reluctance connection, and the upper ends of which are connected together by a relatively high reluctance connection. It will also be apparent that a channel 11^d is formed at the upper end of the stationary core member

by virtue of the fact that the outer laminations of this core member are longer than the inner laminations. The middle leg 11^b of the stationary core member 11 is surrounded by a primary winding P, and the outer leg 11^a is surrounded by a secondary winding S.

The movable core member 12 comprises a stack of laminations each similar to the lamination 15 shown in Fig. 9. This core member is slidably mounted in the channel 11^d, and is provided with a longitudinally extending slot 15^a through which a clamping bolt 16 that is mounted in the upper end of the stationary core member extends, whereby the movable core member may be locked in an adjusted position. The parts are so proportioned that when the movable core member occupies its right-hand extreme position in which it is shown in the drawings, the reluctance of the flux path which includes the leg 11^a and which passes through the secondary winding S will be relatively high, and the reluctance of the leakage path, which path includes the leg 11^c, will be relatively low, but that, when the movable core member occupies its opposite extreme position, the reluctance of the flux path through the secondary winding will be relatively low and the reluctance of the leakage path will be relatively high. It follows, therefore, that by moving the movable core member 12 between its two extreme positions, the equivalent reactance of the secondary winding S of the transformer T² may be varied in the same manner that the reluctance of the secondary winding S of the transformer T¹ shown in Fig. 1 may be varied by moving the movable core member 2.

One feature of the transformer T² is that the laminations at the top of the stationary core have a relatively large area in contact with the movable core member in all positions of the movable core member, thus causing the transformer to have a low magnetizing current.

Referring now to Figs. 10 and 11, the transformer T³ here shown comprises a laminated stationary core member 17 of magnetizable material having three parallel legs 17^a, 17^b and 17^c connected at their lower ends by a backstrap 17^d, and provided at their upper ends with aligned vertical tongues 18^a, 18^b and 18^c. The middle leg 17^b of the stationary core member 17 is surrounded by a primary winding P, and the outer leg 17^a is surrounded by a secondary winding S. The transformer T³ also comprises two movable laminated core members 19 and 20 of magnetizable material which cooperate with the stationary core member on opposite sides of the tongues 18^a, 18^b and 18^c. These movable core members are similar, and each is provided with a longitudinal slot 21 which slidably receives a clamping bolt 22 which is mounted in the middle tongue 18^b. The movable core members are slidably supported on shoulders 23 which are formed on the legs 17^a, 17^b and 17^c on opposite sides of the tongues 18^a, 18^b and 18^c, whereby the movable core members are held in horizontal positions.

With the transformer T³ constructed in the manner just described, it will be apparent that movement of either movable core member toward the right will increase the reluctance of the flux path through the secondary winding and will decrease the reluctance of the leakage path, whereas movement of either movable core member in the opposite direction will produce the opposite effect. It will also be apparent that since each movable core member has a relatively small cross-sectional area, a relatively large movement of

either movable core member will produce a relatively small change in the relative reluctances of the two flux paths, thus providing a non-critical adjustment which permits the equivalent reactance of the secondary winding S to be readily varied by infinitely small amounts.

Referring now to Figs. 12, 13 and 14, the transformer T⁵ here shown comprises a stationary laminated magnetizable core 30 having three parallel legs 30^a, 30^b and 30^c connected together at their lower ends by a backstrap 30^d. The leg 30^c is provided with a primary winding P, and the leg 30^a is provided with a secondary winding S. Formed on the upper end of the legs 30^a and 10 30^c are aligned vertical tongues 31^a and 31^c, respectively, and slidably mounted on shoulders 32 formed on the legs 30^a and 30^c on opposite sides of the tongues 31^a and 31^c are movable core members 33 and 34. Each of these movable core members is provided adjacent its opposite ends with longitudinal slots 35^a and 35^b which slots 20 slidably receive clamping bolts 36 and 37, respectively, mounted in the tongues 31^c and 31^a, whereby the blocks may be clamped in adjusted longitudinal positions relative to the fixed core member. A notch 38 is formed in the under side of each of the movable core members 33 and 34 near the central portions of these blocks in such manner that when the movable members occupy 25 their extreme right-hand positions in which they are shown in the drawings a relatively large air gap is provided between the middle leg 30^b of the stationary core member 30 and each of the movable core members 33 and 34.

With the transformer T⁵ constructed in the manner just described, when the primary winding P is energized, a part of the resultant flux which is set up by the current flowing in this winding will traverse a path which passes 30 through the secondary winding S and which includes the tongue 31^c on the leg 30^c, the movable core members 33 and 34, the tongue 31^a on the leg 30^a, the leg 30^a and the backstrap 30^d, and the remainder of the resultant flux will traverse 35 a leakage path which includes the tongue 31^c on the leg 30^c, the movable core members 33 and 34, the leg 30^b, and the left-hand half of the backstrap 30^d, the amount of the flux which traverses each path being dependent upon the relative reluctances of these two paths. The parts 40 are so proportioned that when both movable core members 33 and 34 occupy their extreme right-hand positions, the flux path through the secondary winding S will have a relatively low reluctance, and the leakage path will have a relatively high reluctance, but that, as either movable member is moved toward the left, the reluctance of the flux path through the leakage path will decrease and the reluctance of the flux path 45 through the secondary winding will increase, until when both members occupy their extreme left-hand positions, the reluctance of the path through the secondary winding will be relatively high, and the reluctance of the leakage path will be relatively low. It follows, therefore, that by adjusting the two movable core members 33 and 34 the relative reluctance of the flux path through the secondary winding and the leakage path 50 may be readily adjusted in a manner to provide any desired variation in the equivalent reactance of the secondary winding between its maximum and minimum reactance.

One advantage of transformers embodying our invention is that since the reluctance of the magnetic path through the secondary winding is in-

creased at the same time that the reluctance of the leakage path is decreased, the equivalent reactance of the transformer may be varied over a much wider range than has heretofore been possible.

Another advantage of transformers embodying our invention is that finer adjustments of the equivalent reactance of the transformers may be made than has heretofore been possible.

Although we have herein shown and described only a few forms of transformers embodying our invention, it is understood that various changes and modifications may be made therein within the scope of the appended claims without departing from the spirit and scope of our invention.

Having thus described our invention, what we claim is:

1. A reactive transformer comprising a stationary core member provided with three parallel legs connected at one end by a backstrap, a movable core member mounted for longitudinal sliding movement between two extreme positions at the ends of said legs opposite to said backstrap in such manner that one flux path is formed by a first one of said legs, a second one of said legs and said movable member and another flux path is formed by said first leg, the remaining leg, and said movable member, and that movement of said member from one extreme position toward the other will simultaneously increase the reluctance of one path and decrease the reluctance of the other path, said movable member being provided adjacent its ends on the side nearest said stationary core member with inclined surfaces which cooperate with the adjacent legs of said stationary core member in such manner that the reluctances of said two flux paths will vary uniformly in response to the movement of said movable member, a primary winding disposed on said first leg only, and a secondary winding disposed on said second leg only.

2. A reactive transformer comprising a stationary core member provided with three parallel legs connected together at their lower ends by a backstrap, a movable core member mounted for longitudinal movement between two extreme positions at the upper ends of said legs in such manner that when said movable core member occupies its one extreme position a low reluctance path will be formed from the one outer leg of said stationary core member to the other outer leg through said movable core member and a high reluctance path will be formed from said one outer leg to the middle leg of said stationary core member through said movable core member, but that movement of said movable core member toward its other extreme position will increase the reluctance of the flux path from said one outer leg to said other outer leg through said movable core member and will decrease the reluctance of the flux path from said one outer leg to said middle leg through said movable core member, a primary winding on said one outer leg, and a secondary winding on said other outer leg.

3. A reactive transformer comprising a stationary core member provided with three parallel legs connected together at their lower ends by a backstrap, the two outer legs of said stationary core member being provided at their upper ends with aligned vertical tongues and with shoulders on one side of said tongues, a movable core member mounted for longitudinal sliding movement on said shoulders and provided in its under side with a notch which forms an air gap between said movable core member and said middle leg.

when said movable core member occupies its one extreme position but not when it occupies its other extreme position, a primary winding on one of said outer legs and a secondary winding on the other outer leg.

5 4. A reactive transformer comprising a stationary core member provided with three parallel legs connected together at their lower ends by a backstrap, the two outer legs of said stationary 10 core member being provided at their upper ends with aligned vertical tongues and with a shoulder on each side of said tongues, two movable core members one mounted for longitudinal sliding movement on the two shoulders on the one side 15 of said tongues and the other mounted for longitudinal sliding movement on the two shoulders on the other side of said tongues, each of said movable core members being provided in its under side with a notch which forms an air gap 20 between such movable core member and said middle leg when such movable core member occupies its one extreme position but not when it occupies its other extreme position, a primary winding on one of said outer legs and a secondary winding on the other outer leg.

25 5. A reactive transformer comprising a stationary core member provided with three parallel legs connected together at their lower ends by a backstrap, the two outer legs of said stationary core member being provided at their upper ends with aligned vertical tongues and with shoulders on one side of said tongues, a movable core member mounted for longitudinal sliding movement on said shoulders and provided in its under side 30 with a notch which forms an air gap between said movable core member and said middle leg when said movable core member occupies its one extreme position but not when it occupies its other extreme position, means for locking said movable core member in an adjusted longitudinal position, a primary winding on one of said outer legs and a secondary winding on the other outer leg.

35 6. A reactive transformer comprising a stationary core member provided with three parallel legs each connected together at one end by a backstrap, a bolt mounted in said middle leg at the end opposite to said backstrap, two movable core members disposed on opposite sides of said middle leg and each provided with a longitudinal slot which slidably receives said bolt, whereby said core members may be moved toward or away from each of said outer legs to adjusted positions and may be locked in their adjusted positions by said bolt, a primary winding on said middle leg, and a secondary winding on one of said outer legs.

40 7. A reactive transformer comprising a stationary core member provided with three parallel legs each connected together at one end by a backstrap and each provided at the other end with a tongue and with a shoulder on each side of said tongue, a bolt mounted in the tongue in said middle leg, two movable core members slidably mounted on said shoulders on opposite sides of said tongues and each provided with a longitudinal slot which slidably receives said bolt, a primary winding on said middle leg and a secondary winding on one of said outer legs.

45 8. A reactive transformer comprising a stationary core member provided with three legs connected at one end by a back strap, a movable core member mounted for longitudinal sliding movement between two extreme positions at the ends 50 of said legs opposite to said back strap in such

manner that a first variable reluctance flux path is formed by a first one of said legs, a second one of said legs and said movable core member, and a second variable reluctance flux path is formed by said first leg, the third one of said legs and said movable member, the parts being so proportioned that said one flux path will have a relatively high reluctance and said other flux path a relatively low reluctance or vice versa according as said movable core member occupies its one extreme position or its other extreme position and that movement of said movable core member will simultaneously vary the reluctances of said two paths in such manner that an increase in the reluctance of either path will be accompanied by a decrease in the reluctance of the other path, a primary comprising a single winding surrounding said first leg only, and a secondary comprising a single winding surrounding said second leg only.

20 9. A reactive transformer comprising a stationary core member provided with three parallel legs, two guide plates secured to the opposite sides of said stationary core member at one end of said legs, a movable core member mounted for longitudinal sliding movement between two extreme positions in the channel formed by said guide plates in such manner that one flux path is formed by a first one of said legs, a second one of said legs and said movable core member and another flux path is formed by said first leg, the remaining leg and said movable core member, and that movement of said movable core member from one extreme position toward the other will simultaneously increase the reluctance 30 of one path and decrease the reluctance of the other path, means for moving said movable core member between its two extreme positions, means associated with said plates for locking said movable core member in any position to which it is moved, a primary winding surrounding said first leg, and a secondary winding surrounding said second leg.

35 10. A reactive transformer comprising a stationary core member provided with three parallel legs, two guide plates secured to the opposite sides of said stationary core member at one end of said legs, a movable core member mounted for longitudinal sliding movement between two extreme positions in the channel formed by said 40 guide plates in such manner that one flux path is formed by a first one of said legs, a second one of said legs and said movable core member and another flux path is formed by said first leg, the remaining leg and said movable core member, and that movement of said movable core member from one extreme position toward the other will simultaneously increase the reluctance of one path and decrease the reluctance of the other path, means mounted in one of said guide 45 plates and operatively connected with said movable core member for moving said movable core member between its two extreme positions, a bolt extending through and cooperating with said plates in such manner that when said bolt is tightened said movable core member will be firmly locked in any position to which it is moved, a primary winding mounted on said first leg, and a secondary winding mounted solely on said second leg.

50 11. A reactive transformer comprising a stationary core member provided with three parallel legs connected together at one end by a back strap, two guide plates secured to the opposite sides of said stationary core member at 55

the free ends of said legs, the one guide plate being provided at one end with a lateral extension and at each end with a longitudinally extending slot, and the other guide plate being provided at each end with a longitudinally extending slot which aligns with one of the slots in the opposite guide plate, a movable core member mounted in the channel formed by said guide plates for longitudinal sliding movement between two extreme positions in such manner that one flux path is formed by a first one of said legs, a second one of said legs and said movable core member and another flux path is formed by said first leg, the third leg and said movable core member, and that movement of said movable core member from one extreme position toward the other will simultaneously increase the reluctance of one path and decrease the reluctance of the

other path, two bolts extending through said movable core member adjacent its ends and co-operating with the inner ends of the aligned slots in said guide plates to prevent movement of said movable core member beyond its extreme positions, a screw threaded rod fastened at one end to said movable core member by one of said bolts and provided at its other end with a thumb nut rotatably mounted in said lateral extension of said one guide plate, whereby by turning said thumb nut in opposite directions said movable core member may be moved to any position between its two extreme positions, a primary winding mounted on said first leg of said stationary core member, and a secondary winding mounted on said second leg of said stationary core member. 5 10 15

SAMUEL M. LUCAS.
